DRAGLINE EXCAVATOR

Mitchell L. Fykse, South Milwaukee, Wis., assignor to Bucyrus-Erie Company, South Milwaukee, Wis., a corporation of Delaware

Application August 30, 1934, Serial No. 742,053

5 Claims. (Cl. 37—116)

My invention relates primarily to dragline excavators.

Dragline excavators are well known in the art. They consist of a main platform carrying the actuating machinery, there being a boom, swingable in a vertical plane, carried at one end of said platform. The outer point of the boom carries a vertical sheave, either pivoted in the boom, with no provision for side swing, or else pivoted in a yoke, which in turn depends from a substantially horizontal axis in the vertical plane of the boom. About this sheave is reeved the hoist-rope, which serves to raise and lower the digging bucket.

Neither of the older constructions, as outlined above, allows the resultant of the pull of the hoist-rope on the sheave, and of the boom-suspension-cables on the end of the boom to pass through an unvarying point on the boom, regardless of the distance of the bucket from the main platform, and regardless of the inclination of the boom, and regardless of the working distance of the bucket "off-side" of the vertical plane through the boom. This failure necessarily introduces both bending stresses and torsional stresses in the boom. These stresses and torsions are eliminated in my invention.

Furthermore the use of a longitudinal pivot for the hoist sheave requires the inclusion of several heavy diaphragms across the boom, to hold the bearings for said longitudinal pivot, thereby adding to the dead weight of the boom.

In my invention, the only pin in contact with the boom is a transverse one, which requires no such heavy auxiliary diaphragms for its support, as it is held directly by the main boom members. I therefore have thus reduced the necessary weight of the boom.

Also, the action of my sheave-yoke, in swinging "fore and aft" in a vertical plane and/or to either side, in response to the "lead" of the hoist cable, when the bucket is at varying positions with respect to the machine, retains the desirable characteristic of having the resultant load on my sheave pin always pass through the center of the supporting pin on the boom, said center point being on the neutral axis of the boom. And, inasmuch as my boom suspension is also brought to an axis passing through this same point, there is no bending moment imposed upon the boom, and the torsional loading on the boom is completely eliminated.

In addition to my principal objects, as enumerated above, I have worked out a number of

novel and useful details, which will be readily evident as the description progresses.

My invention consists in the novel parts, and in the combinations and arrangements thereof, which are defined in the appended claims; and of which one embodiment is exemplified in the accompanying drawing, which is hereinafter particularly described and explained.

Throughout the description, the same reference number is applied to the same member or to similar members.

Referring to the drawing, it will be seen that Figure 1 shows a side elevation of my invention, part being in section, as indicated by line 1—1, in Figure 2.

Figure 2 shows a vertical section of my invention, as indicated by the line 2—2, in Figure 1.

Figure 3 is a simplified representation of a dragline embodying my invention.

It will be seen that the boom 10 comprises two side plates 11, which are stiffened against lateral bending by the angle pieces 12, which are located on the upper side of the boom 10.

At the upper end of the boom, each side plate 11 carries on its outer face a fixed bearing 13, which carries non-rotatably the bearing-block-pin 14, the said pin being transverse to the boom.

Rotatably mounted at the outer ends of this bearing-block pin 14, and symmetrically positioned with respect to the vertical plane through the neutral axis of the boom, are the boom-suspension sheaves 15, of which there may be more than are shown, if the boom-suspension cable is to be many-part.

Between the two side-plates 11 of the boom, and centrally spaced, with respect to the side-plates, by the spacers or sleeves 16, there is a bearing-block 17, rotatably carried by the pin 14.

Integral with the bearing block 17 is a pair of axially aligned trunnions 18. The axis of the trunnions 18 and the axis of the pin 14 perpendicularly bisect each other, the point of bisection being on the neutral axis of the boom. The axis of the trunnions is therefore always in a vertical plane through the said neutral axis.

The trunnions 18 carry, depending therefrom and mounted for swinging thereon, a yoke 19, which supports at its lower end a hoist-sheave-pin 20, upon which the hoist-sheave 21 is rotatably carried.

The hoist-sheave-pin 20 also supports rotatably a depending bucket 22, to which the dead end of the hoist-rope 23 is secured.

As the hoist-sheave-pin 20 is always at right angles to the axis of the trunnions 18, which lat-

- ter is always at right angles to the axis of the bearing-block-pin 14, and as the rotation of the yoke 19 about either or both axes is preferably free, it is obvious that the hoist-sheave-pin 20 is not constrained to remain parallel to the bearing-block-pin 14, but may take a position such that the hoist-sheave 21 is free to set itself in the plane of the leads of the hoist-ropes 23, whatever may be the distance that the bucket 24 is 10 "off-side" of the center-line of the main machine.

Also, because of this complete freedom of positioning of the yoke 19 and the hoist-sheave 21, it is obvious that the center line of the yoke 19 is quite free to set itself in the line of the resultant of all the forces acting on the yoke; so that there is perfect delivery of the hoist-rope to the hoist-sheave, whatever may be the position of the bucket.

The boom-suspension cables 25 are reeved 20 about the sheaves 15.

Furthermore, as the forces on the boom-point—which are the weight of the yoke and sheave, the resultant of the tensions in the various reaches of the hoist-rope in any operating position thereof, and the resultant of the boom-suspension forces—all pass through the same point, viz., the point 26, which is the intersection of the center line of the bearing-block-pin 14 with the center line of the trunnions 18, it is 25 obvious that the boom will act merely as a column; that is, the loading, however departing from the vertical, will introduce merely compressional stresses, but no bending, into the boom.

Furthermore, because of the perfect freedom 30 of the yoke to set itself in the line of the resultant of all forces upon it even when the bucket is "off-side", there can be no torsional stresses imposed upon the boom by the load.

Even if the axis of the trunnions 18 were, for 35 any reason, such as constructional considerations, slightly offset from exact intersection with the axis of pin 14) there would still be no bending ample, still in the central vertical plane of the boom, but passing a short distance above the axis of pin 14) there would still be no bending moment introduced into the boom, and only a negligible torsion, when the bucket is "off-side".

Having now described and illustrated one form 40 of my invention, I wish it to be understood that my invention is not to be limited to the specific form or arrangement of parts hereinbefore described, except in so far as such limitations are specified in the appended claims.

I claim:

1. In a dragline excavator, the combination of: a main frame; a boom extending therefrom; a transverse horizontal pin at the outer end of the boom; boom-suspension sheaves, mounted on said pin; a pair of trunnions perpendicular to said pin and pivotally mounted thereon; a yoke pivotally

mounted on the trunnions, and depending therefrom; a transverse pin in the yoke; a hoist-sheave pivoted thereon; a hoist-rope, extending from the main frame directly around the hoist-sheave, and thence to an operative association with the bucket; and a boom-suspension-cable, reeved about the boom-suspension sheaves.

2. In a dragline excavator, the combination of: a main frame; a boom extending therefrom; a universal joint at the outer end of the boom; 10 sheave-supporting means, depending from said universal joint; a hoist-sheave therein; boom-suspension sheaves, having their axes in substantial alignment with the transverse axis of the universal joint; a hoist-rope, extending from the main frame directly around the hoist-sheave, and thence to an operative association with the bucket; and a boom-suspension-cable, reeved about the boom-suspension sheaves.

3. In a dragline excavator, the combination of: 20 a main frame; a boom extending therefrom; a transverse horizontal pin at the outer end of the boom; boom-suspension sheaves, mounted on said pin; a pair of trunnions perpendicular to said pin and pivotally mounted thereon, and having its 25 trunnion-axis intersect the axis of the pin; a yoke pivotally mounted on the trunnions, and depending therefrom; a transverse pin in the yoke; a hoist-sheave pivoted thereon; a hoist-rope, extending from the main frame directly around the 30 hoist-sheave, and thence to an operative association with the bucket; and a boom-suspension-cable, reeved about the boom-suspension sheaves.

4. In a dragline excavator, the combination of: a main frame; a boom extending therefrom; a 35 hoist-sheave; means suspending the hoist-sheave from the outer end of the boom for sidewise swinging movement; means suspending the sheave for fore-and-aft swinging movement; boom-suspension means; and a hoist-rope, extending from the main frame directly around the hoist-sheave, and thence to an operative association with the bucket; the various elements being so positioned that the line of resultant tension in the hoist-rope, the line of resultant tension in the 45 boom-suspension means, and the line of compression of the boom will substantially intersect.

5. In a dragline excavator, the combination of: a main frame; a boom extending therefrom; a universal joint at the outer end of the boom; 50 sheave-supporting means, depending from said universal joint; a sole hoist-sheave swiveled in said sheave-supporting means below the point of suspension thereof; boom-suspension means, secured to the boom at points in substantial alignment with the transverse axis of the universal joint; and a hoist-rope passing directly from the main frame over the hoist-sheave, and thence downwardly to support the bucket.
